Attorney.

UNITED STATES PATENT OFFICE.

BERNARD P. SEEGER, OF SAN FRANCISCO, CALIFORNIA.

HOSE SUPPORTER.

Application filed October 19, 1922. Serial No. 595,588.

To all whom it may concern:

Be it known that I, BERNARD P. SEEGER, a citizen of the United States, and a resident of San Francisco, county of San Francisco, State of California, have invented a new and useful Hose Supporter, of which the following is a specification.

My invention relates to a hose supporter and has for its primary object to provide a device of this character which may be worn with the utmost convenience, and overcoming the many disadvantages heretofore experienced with such devices.

The salient features and the advantages of the invention will be appreciated upon reference to the accompanying drawing in which Figure 1 is a view illustrating the application of the device; Figure 2 is a perspective view of the device; Figure 3 is a front view of the anti-slipping member which represents the important part of the device; and Figure 4 is an inside view of the anti-slipping member.

Referring now to the drawing in detail (5) represents a leg encircling member which I prefer to make in the form of an elastic band with the end (6) thereof preferably permanently attached to a connecting pin, or the like (7), which is carried by the ring (8) imbedded in the anti-slipping member (9). The opposite end of the band (5) is made with a detachable connection between the button (10), also carried by the ring (8) so that the band (5) may be connected around the leg of the wearer and detached therefrom. The particular connection carried by the respective ends of the band (5) and the attachments to hold the same to the anti-slipping member are immaterial.

The anti-slipping member is preferably made in the form of a rubber suction cup with the ring (8) imbedded therein so as to form a rugged connection for the buttons or the like (7) and (10). It is to be noted that the buttons (7) and (10) are mounted at the sides of the center of the anti-slipping device, and that a third button (11) is mounted on the anti-slipping member in the center thereof on the outer closed side of the cup, and below the buttons (7) and (10). The button (11), or whatever other anchoring means may be used is made to connect or attach the end of the hose supporting strap (12) which carries a suitable

device (13) on its free end for connecting with the hose.

The inside of the anti-slipping member is cupped out as at (14) to realize a certain amount of suction effect, and the cupped out part leaves an annular surface (15) which is preferably corrugated to aid in preventing slipping.

The particular kind of band (5) or strap (12) or the attaching buttons and associated parts is immaterial, as previously mentioned, and the salient features of the invention reside in providing an anti-slipping member which is preferably made as stated in the form of a rubber suction cup or disc.

In use the anti-slipping member contacts directly with the leg of the wearer and a certain suction effect is realized which prevents it from slipping; consequently the supporter holds the hose up without necessitating a tightening of the band (5) to such an extent that it would be uncomfortable.

For a so-called double supporter, two of the anti-slipping members may be used one on each side of the leg with a strap such as (12) suspended from each. In this instance two anti-slipping members should be connected together and the band (5) fixed to one and detachably fixed to the other.

I claim:

1. A hose supporter comprising a rubber suction cup, a leg encircling band attached to the outside of the cup at opposite points within its marginal edge whereby the cup may be held against the leg for suctional functioning thereagainst, and a hose engaging strap suspended from the outer closed side of the cup.

2. A hose supporter comprising a rubber suction cup, a leg encircling band attached to the outside of the cup at opposite points within its marginal edge whereby the cup may be held against the leg for suctional functioning thereagainst, and a hose engaging strap suspended from the outer closed side of the cup and from a point also within the marginal edge thereof.

3. A hose supporter comprising a suction cup, a leg-encircling band attached to the cup for holding the hollow portion thereof directly against the leg so that by the action of induced suction the cup will be held against vertical movement on the leg, and a depending hose-engaging element connect-

ed with the closed side of the cup, the cup attachment of the band with the cup, said 15 having a ring embedded therein and provided with means to effect the aforesaid attachment of the band with the cup.

5. 4. A hose supporter comprising a suction cup, a leg-encircling band attached to the cup for holding the hollow portion thereof directly against the leg so that by the action of induced suction the cup will be held 10 against vertical movement on the leg, and a depending hose-engaging element connected with the closed side of the cup, the cup having a ring embedded therein and provided with means to effect the aforesaid

attachment of the band with the cup, said 15 means consisting of buttons disposed above the horizontal center of the cup.

5. A hose supporter comprising a rubber suction cup, a leg encircling band attached to the outside of the cup at opposite points 20 within its marginal edge whereby the cup may be held against the leg for suctional functioning thereagainst, and a hose engaging strap suspended from the outer closed side of the cup and from a point also within 25 the marginal edge thereof and below the attachment points of the band aforesaid.

BERNARD P SEEGER
